Filed May 31, 1968, Ser. No. 12,149

Term of patent 14 years

Int. Cl. D30—02

U.S. Cl. D30—13

FIGURE 1 is a perspective view of an animal feed machine incorporating my new design.

FIG. 2 is an end view of the machine as seen from the right of FIG. 1.

FIG. 3 is a side elevational view of the machine.

The undisclosed side of the machine is a mirror image of the side shown, and the undisclosed end is substantially the same in appearance as the disclosed end except for the fitting.

I claim:

The ornamental design for an animal feed machine, as shown and described.
